UNITED STATES PATENT OFFICE

HARRY W. NEAL, OF INDIANAPOLIS, INDIANA, ASSIGNOR TO HALL-NEAL FURNACE COMPANY, OF INDIANAPOLIS, INDIANA

FURNACE DRUM

Application filed October 21, 1929. Serial No. 401,073.

This application relates to furnaces particularly of the type adapted to heat buildings by currents of warm air and is directed to a radiating drum employed in connection therewith.

It is the primary object of the invention to provide a conducting and radiating surface that may be heated directly from one side and a current of air drawn across the other side without intervening joints therebetween.

Another important object is the building up of a heating surface from a plurality of sections to provide integrally formed radiating fins. Other objects reside in the unique formation of a drum from sheet metal that may be air tight and extremely durable under all of the conditions encountered in a furnace.

These and other objects will become apparent in the following description of the invention as illustrated by the accompanying drawings, in which—

Fig. 1 is a front elevation of a furnace to which my invention is applied and with the outer housing removed;

Fig. 2, a rear elevation;

Fig. 3, a horizontal transverse section on the line 3—3 in Fig. 1;

Fig. 4, a vertical section on the line 4—4 in Fig. 3; and

Fig. 5, a vertical section on the line 5—5 in Fig. 4.

Like characters of reference indicate like parts throughout the several views in the drawings.

I preform lengths of sheet metal 10 to have outwardly extending fins 11 and 12. By grouping a plurality of these lengths 10 to have the backs form a continuous line with the adjacent fins contacting one another, I form the outer side of a drum 13, by welding along the extreme outer edges of the fins and across their tops and bottoms.

Each of the lengths or sections 10 are preformed to the desired curvature of the completed drum. The opposite wall of the drum 13 is formed in a similar fashion by placing together one after another the sections 14 each having the out-turned fins 15 and 16 in respective contact one with another and

welded one to the other around their outer edges, the entire welding operation being confined along the edges and not on the side faces. The two walls so formed are united by the end pieces 17 and 18 each having vertically disposed fins adapted to contact the fins at the end of each of the walls and to be welded thereto along their edges.

It is to be observed that this structure not only provides for the side walls of the drum but also gives radiating fins from both sides of the drum that are integral extensions from the side walls and that are not separated therefrom by joints or air gaps. It is also to be noted that each fin, being formed from the two adjacent fins is twice the thickness of the wall of the drum itself.

At the top and bottom ends of the walls are the sheet metal closures 19 and 20, U-shaped in cross section to have outwardly turned flanges with faces in direct contact with the vertical faces of the inner and outer walls. These two closures are held in place and united to the various sections 10 and 14, by welding along the extreme edges of the sections and legs of the two closures. By welding along the edges of two pieces of metal having substantial contacting area back of the edges, the welding operation is reduced to a minimum as well as being easier to perform than where one piece of metal abuts another, and additionally permits the forming of a joint that may be readily observed to be air tight without having to undergo tests.

The upper and lower closures 19 and 20 unite the various sections 10 and 14 into a rigid unitary structure, that though light in weight is extremely durable.

I employ the usual type of fire box and dome 30, and preferably use two drums constructed as above explained. From the upper forward part of the dome 30 I provide two outwardly projecting flues 21 and 22 and by means of the attaching flanges 23 and 24 secure thereon the connections 25 and 26 of the drums 13, Fig. 1. The connections 25 and 26 are in the upper forward ends of the drums.

The drums 13 are spaced outwardly from

the dome by means of the above described attachment and curve around the dome to have their rear ends approach one another. Discharge flues 28 and 29 lead from the lower rear ends respectively of the drums 13 and are carried around rearwardly in parallel relation one with the other to discharge into the collecting box 40 from which there is a flue pipe opening 31. It is to be noted that the adjacent walls of the flues 28 and 29 form a dividing wall 32 in the box 40 whereby the escaping gases enter the box in two streams flowing in the same direction so that no turbulence is produced by conflicting currents.

10 The drums are preferably supported at the rear by extending ears 33 and 34 from one of the fins 15 on each drum to be engaged by bolts 35 passing through the ears and brackets 36 fixed on the dome 30.

15 I claim:

20 1. A furnace drum comprising a plurality of sheet metal sections each having a fin out-turned from each of the two vertical edges, said sections being united consecutively one to another by having adjacent fins contacted and secured one to the other, and said sections being shaped one after another between said fins to define the shape 25 of the drum.

25 2. A furnace drum comprising a plurality of sheet metal sections each having a fin out-turned from each of the two vertical edges, said sections being united consecutively one to another by having adjacent fins contacted and secured one to the other, and said sections being shaped one after another between said fins to define the shape 30 of the drum, said legs being extended an appreciable distance from said sections to form radiating fins about the drum.

35 3. A furnace drum comprising a plurality of sheet metal sections each having a fin out-turned from each of the two vertical edges, said sections being united consecutively one to another by having adjacent fins contacted and secured one to the other, and said sections being shaped one after another between said fins to define the shape 40 of the drum, and top and bottom closures each having a flange turned outwardly from its edge therearound to contact and be secured to said sections.

45 4. A furnace drum comprising a plurality of sheet metal sections each having a fin out-turned from each of the two vertical edges, said sections being united consecutively one to another by having adjacent fins contacted and secured one to the other, and said sections being shaped one after another between said fins to define the shape 50 of the drum, said fins being extended an appreciable distance from said sections to form radiating fins about the drum, and

55 said fins being secured one to the other by welding their adjacent outer edges only.

5. In a furnace, a fire-box having a pair of upper, forwardly discharging flues, a radiating drum on each side of the fire-box spaced therefrom and connected with said flues at their upper forward ends, a collecting box at the rear of the fire-box, discharge flues leading from the rear ends of said drums and entering said collecting box 70 one flue parallel to the other, and radiating fins projecting inwardly from said drums toward said fire-box, said fins terminating at a distance from the fire-box, and ears extending from fins and secured to the fire-box. 75

6. In a furnace, a fire-box having a pair of upper, forwardly discharging flues, a radiating drum on each side of the fire-box spaced therefrom and connected with said flues at their upper forward ends, a collecting box at the rear of the fire-box, discharge flues leading from the rear ends of said drums and entering said collecting box one flue parallel to the other, and radiating fins projecting inwardly from said drums toward said fire-box, each of said drums being built up of a plurality of preformed sheet metal sections individually shaped to conform to the shape of the fire-box, the vertical edges of each section being out-turned to contact corresponding edges of adjacent sections, said out-turned edges being united to form said fins. 90

105 In testimony whereof I affix my signature.

HARRY W. NEAL.
